UNITED STATES PATENT OFFICE.

ARTHUR C. LINDHOLM, OF SPRINGFIELD, MASSACHUSETTS.

GRINDING ATTACHMENT FOR REAMERS.

Application filed December 27, 1922. Serial No. 609,321.

My invention relates to improvements in devices, appliances, or attachments which are designed to be connected and used with grinders or grinding machines, and consists essentially of a main-supporting member or knee that is attachable to a fixed member of a grinder, and carries the other parts and members or elements of the attachment, a carriage slidably arranged on said knee, with actuating means for said carriage, a table slidably arranged on said carriage, with actuating means for said table, and a work holder mounted on and pivotally connected with said table, adapted to be adjusted thereon about its pivot, and consisting in part of direct supporting and centering means for a reamer while being ground, which means is adjustable, together with such other parts and members as may be necessary or desirable in order to render the attachment complete in every respect, all as hereinafter set forth.

The main-supporting member or knee of this attachment is designed to be secured preferably to the front side of the grinding-wheel stand of a grinder, and the movable and adjustable parts and members supported by said knee are adapted to support and carry a reamer in operative position relative to the grinding-wheel of such grinder, and while said reamer is being ground. The carriage is capable of having imparted thereto a cross feed or in-and-out movement, while the table is capable of having imparted thereto a feed or movement at right-angles to said first-mentioned feed or movement.

The primary object of my invention is to produce an appliance which is adapted readily to be attached to or connected with a grinder, and when so attached or connected to carry a reamer in grinding position relative to the grinding-wheel of such grinder, said appliance being simple both in construction and operation, convenient, and capable of so supporting and moving a reamer during the grinding operation that said reamer is expeditiously and accurately ground. The appliance as a whole is as readily detachable from the grinder as attachable to the same.

Another object is to produce an attachment of this character which is so constructed that all except the primary supporting member can easily and quickly be removed, and as easily and quickly restored to position,

such member remaining permanently in place, and consisting of the knee hereinbefore referred to.

A further object is to provide the attachment with means whereby straight-blade, tapered, and even spiral, reamers can be ground and sharpened.

Still another object is to afford the attachment with means for easily and quickly adjusting the parts and members thereof to whatever extent may be required.

The attachment is strong and durable without being heavy and cumbersome.

Other objects and advantages will appear in the course of the following description.

I attain the objects and secure the advantages of my invention by the mechanism illustrated in the accompanying drawings, in which—

Figure 1 is a top plan of a grinding attachment for reamers which embodies a practical form of my invention, showing the same supported from the grinding-wheel head or stand of a grinder, and a reamer carried by said attachment in the act of being ground; Fig. 2, a top plan of the main-supporting member or knee of said attachment; Fig. 3, an enlarged, fragmentary, sectional detail of the actuating means for the carriage of said attachment; Fig. 4, a front elevation of said attachment; Fig. 5, a right-hand end elevation of the attachment, wherein one of the work-holding arms is broken off and the reamer shown in cross section, and, Fig. 6, an enlarged, transverse section through the knee and carriage and longitudinal section through the table of the attachment.

Similar reference characters designate similar parts throughout the several views.

In Figs. 1, 4, and 5, a portion of the bed of a grinder is represented at 1, and mounted on this bed is a grinding-wheel stand or head 2. Journalized in the head 2 is a shaft 3 which is driven by the pulley 4 and a belt 5, said pulley being secured on one protruding terminal of said shaft, as will be seen upon referring to the first view. Secured to the opposite protruding terminal of the shaft 3 is a grinding wheel 6. All of these parts and members in construction and operation are old and well-known. There is also shown in Figs. 1 and 5 a reamer 7 having teeth 8 for the grinding of which my attachment is designed.

I illustrate in connection with the attach-

ment an indexing device and will subsequently explain the same, but such device forms no part of said invention, and might be replaced with any other device of similar 5 nature or for a similar purpose.

The main-supporting member of the attachment is in the form of a knee 9 which is provided at the rear end with upwardly- and downwardly-projecting flanges 50 and 51, 10 respectively, that are bolted, as clearly shown at 10 in Figs. 1 and 5, to the front side of the head or stand 2. Thus the knee 9 is firmly and securely attached to the stand 2 and projects forwardly therefrom beyond 15 the base of said stand and the front edge of the bed 1. Usually this knee is left in place when the other parts and members of the attachment are removed, although said knee can itself be removed readily, if desired, by simply taking out the bolts 10. The longitudinal edge portions of the knee 9 form guides 11—11 having inwardly converging sides. A carriage 12 is provided 20 in the under side with a transverse slot or guideway of a shape and size which is adapted to receive the guides 11, so that said carriage can slide back and forth on the knee 9 while being securely held in place 25 thereon. A shim 13 is provided as usual between the inclined side of one of the guides 11 and the adjacent inclined side of the slot in the carriage 12. There is a longitudinal slot 14 in the knee 9, and a horizontal, screw-threaded bushing or nut 49 is securely fixed 30 in the front end of said knee, in the vertical center thereof.

The carriage 12 is arranged on the knee 9 in such a manner that the ends of said carriage project some distance beyond the sides 40 of said knee. Extending longitudinally through the carriage 12, and opening through the top thereof, is a slot or guideway provided to receive a guide 15 on the under side of a table 16, said guideway and guide 45 having inclined sides similar to the sides of the guides 11 and the slot which receives the same, and a shim 17 is also provided as in the other case. A rack 18 is cut in the under side of the table 16 in the longitudinal center thereof. The rack 18 extends some 50 distance to the left from the right-hand end of the table 16. Journaled in the carriage 12 is a shaft or spindle 19. The spindle 19 extends transversely of the carriage 12 55 and is located adjacent to the right-hand end of said carriage. Secured to the spindle 19 in position to intermesh with the rack 18 is a gear 20, the carriage 16 being recessed at 21 to accommodate said gear. The spindle 19 extends beyond the front side of the carriage 12, and a hand-wheel 22 is secured 60 on this protruding terminal of said spindle. Upon rotating the spindle 19 in one direction, by means of the hand-wheel 22, the 65 gear 20 causes the rack 18 and with it the

table 16 to be actuated in one direction on the carriage 12, and, upon rotating said spindle in the opposite direction, said table is caused to be actuated in the opposite direction.

An angular member, which forms an apron 23, projects forwardly from the front side of the carriage 12 in the vertical center thereof, and then downwardly. A screw 24 passes through the depending arm of the apron 23 and through the nut 49 into the slot 14 in the knee 9. The screw 24 is provided at the front end with a hand-wheel 25, and there is a nut 26 on said screw behind the depending arm of the apron 23. The hub of the hand-wheel 25 is in contiguity with the front side and the nut 26 is in contiguity with the back side of the aforesaid arm, consequently said hub and nut prevent the screw 24 from moving longitudinally. When, therefore, the hand-wheel 25 and screw 24 are rotated in one direction, said screw, being in engagement with the fixed nut 49, carries the apron 23 and with it the carriage 12 forwardly, and, when said hand-wheel and screw are rotated in the opposite direction, said carriage is actuated rearwardly.

A work holder is adjustably mounted on the bed 16, and said holder comprises a base 27 from which arise a pair of split bearings 28, a horizontal rod or bar 29 mounted in said bearings, arms 30 and 31 each having a split hub 32 that is mounted on said bar, a centering member 33 carried by said first-named arm, and a centering member 34 carried by said second-named arm.

The work-holder base 27 is pivoted centrally at 35 to the table 16, and in said base adjacent to the ends thereof are two arcuate slots 36, said slots being struck from the axial center of the pivot. The superficial area of the base 27 corresponds with that of the table 16, consequently the slots 36 open onto said table. A bolt 37 passes downwardly through each slot 36 and is tapped into the table 16, a washer 38 being interposed between the head of said bolt and the top of the base 27. Upon loosening the bolts 37, the base 27 can be swung about its pivot 35 in either direction to the extent permitted by said bolts and the ends of the slots 36. After the base 27 has been thus adjusted to the extent required, the bolts 37 are again tightened to hold said base securely in its new relationship or position on the table 16. Adjustment of this kind is necessary when a tapered reamer is to be ground.

The bar 29 extends lengthwise of the base 27, projects beyond the split bearings 28, and may be adjusted on its axis or lengthwise in said bearings to whatever extent may be desired. Bolts 39—39 pass

through the forward split portions of the bearings 28 and are tapped into the rear split portions thereof, and when said bolts are tightened the split portions are drawn closer together and caused to grip the bar 29 with sufficient force to hold the same securely in place. Additional bolts 39 are provided for and similarly applied to the split hubs 32, for the purpose of fastening said hubs rigidly to the bar 29, and enabling the hubs to be adjusted endwise and circumferentially on said bar. The arms 30 and 31 extend downwardly and rearwardly from the bar 29.

15 The centering member 33 is arranged horizontally in the free terminal of the arm 30 and parallel with the bar 29, said member being tapped into and through said arm so that the former can be adjusted to increase 20 or decrease the space between it and the centering member 34. The centering member 33 is provided with an angular head 40 to facilitate adjusting said member with the aid of a wrench or other implement. A 25 thumb-screw 41 is tapped into the arm 30 in position to enable the same to engage the centering member 33 for the purpose of locking the same after adjustment. The centering member 34 is fixed in the free 30 terminal of the arm 31 in proper position, and projects from the inner face of said arm as the centering member 33 projects from the inner face of the arm 30. The arms 30 and 31 must necessarily be adjusted so as to 35 locate the axes of the centering members 33 and 34 in the same straight line.

The reamer 7 is placed in the holder, while the centering member 33 is retracted, by permitting the apex of the centering 40 member 34 to enter the center hole at the leading end of said reamer, and then rotating the centering member 33 in the direction necessary to cause the same to move inwardly or to the right until its apex enters 45 the center hole in the opposite end of said reamer, when the thumb-screw 41 is tightened. The reamer 7 is now carried on and between the centering members 33 and 34, with the axis of said reamer in line with the 50 axes of said members, and can be rotated on the supports thus provided. The construction and arrangement of the parts are such that the reamer is supported in front of the periphery of the grinding-wheel 6, in 55 position to have the teeth 8 ground thereby.

The indexing device for the reamer 8, herein shown, comprises an angular rod 42, which has its vertical arm set in a boss 43 on the arm 31, a head 44 mounted on the horizontal arm of said rod, and a vertical finger 45 supported by said head. The vertical arm of the rod 42 is held in place in the boss 43 by means of a set-screw 46, which is tapped into and through the outer face of

the arm 31 in position to engage said rod. Upon loosening the set-screw 46, the rod 42 can be adjusted on its vertical axis, or raised and lowered, to whatever extent may be necessary, or removed from the arm 31 altogether. The head 44 is secured to the horizontal arm of the rod 42 by means of a thumb-screw 47, and upon loosening said thumb-screw said head may be adjusted outwardly or inwardly and on the axis of said arm. The finger 45 is secured to the head 44 by means of a thumb-screw 48. The finger 45 or at least the lower terminal portion thereof is preferably resilient. By means of the several adjustments just described, the finger 45 can be set to engage with its lower edge the tooth 8 which is on the back side of the reamer 7 and approximately in the horizontal central plane thereof. This is the position in which each tooth 8 is ground, and the finger assists in holding the reamer with the tooth being ground in proper position during the grinding operation. After one tooth is ground, the reamer is partially rotated to bring the next following tooth into grinding position, the finger yielding as the second tooth passes the free end of said finger into position under the same.

For grinding spiral gears, the indexing device described above is removed from the arm 31 and placed in a support suitably situated elsewhere on the grinder proper.

The reamer 7 being of the ordinary type having teeth the cutting edges of which describe a cylinder, it is necessary that the work holder be positioned with the longitudinal edges of the base 27 in parallel relation or coinciding with the corresponding edges or sides of the table 16. When, however, the reamer to be ground is tapered or conical, it is necessary to adjust the holder on the table 16, in the manner hereinbefore explained, to the extent necessary to position said reamer, assuming that the latter be in place between the centering members 33 and 34, at the proper angle to the axis of the grinding-wheel 6 to enable said wheel to grind the teeth of said reamer at the required angle longitudinally. The reamer and holder are adjusted together since the former is supported by the arms 30 and 31 from the bar 29 which is rigidly mounted on or in said holder.

The reamer 7 is placed in position when the carriage 12 is far enough forward so that said reamer does not contact with the grinding-wheel 5. Then, when the reamer is in place, the carriage 12 is actuated rearwardly to bring said reamer against the periphery of the grinding-wheel, said carriage being moved forwardly and rearwardly by means of the hand-wheel 25. The table 16 is actuated to the left, by means of the hand-wheel 22, far enough to locate the

leading end of the reamer 7 in position for the grinding-wheel 6 to commence operation on one of the teeth 8, and then said hand-wheel is rotated in the opposite direction to cause said table to be moved to the right a distance approximately equal to the length of said teeth, with the result that the tooth which is in contact with the grinding-wheel is ground throughout its entire length. 5
10 The amount of material taken off of the tooth is determined by the amount of backward movement imparted to the carriage 12. After one tooth is ground, the carriage 12 is actuated forwardly and the table 16 is actuated to the left into their former positions, the reamer is partially rotated to present the next succeeding tooth in grinding position, and the operations by means of which the first tooth was ground are repeated for the 15 grinding of the second tooth. These operations are continued until all the teeth have been ground, after which the centering member 33 is rotated in the direction to release and take it out of the way of the head 20 of the reamer, and the latter is removed from the attachment. 25

It will be clearly apparent, from the description heretofore given, that the bar 29, with the arms 30 and 31 and the indexing 30 device mounted on said arm 31, together with the reamer supported by the centering members at the free ends of said arms, moves longitudinally with the base 27 and the table 16 when the latter is actuated in either direction. 35

The attachment may be used for grinding tools other than reamers, or for any purpose for which the same is adapted.

More or less change in the shape, size, construction, and arrangement of some or all 40

of the parts of this attachment, besides those hereinbefore specifically pointed out, may be made without departing from the spirit of my invention or exceeding the scope of what is claimed. 45

What I claim as my invention, and desire to secure by Letters Patent, is—

1. The combination, in an attachment of the class described, with a bed, a vertical grinding-wheel stand mounted on said bed, 50 and a horizontal support attachable at one end to the front side of said stand above said bed, and extending outwardly from said stand clear of and otherwise unsupported by the grinder, of work-holding means movably mounted on said support, in operative position relative to the grinding-wheel. 55

2. The combination, in an attachment of the class described, with a bed, a grinding-wheel stand mounted on said bed, and a horizontal support attachable at one end to said stand above said bed, of a carriage slidably arranged on said support, actuating means for said carriage, a table slidably arranged on said carriage, means to actuate said table, 60 and a work-holder mounted on said table, said work-holder comprising a base provided adjacent to its ends with bearings, a bar mounted and longitudinally adjustable in said bearings, arms mounted and laterally 65 adjustable on said bar, and work-engaging members carried by said arms. 70

3. In an attachment, of the class described, a horizontal supporting member having at the rear end vertical flanges 75 adapted to be attached to one side of a vertical stand of a grinder, and also having carriage guides.

ARTHUR C. LINDHOLM.
